UNITED STATES PATENT OFFICE.

HERMAN A. SPERLICH, OF HIGHLAND PARK, MICHIGAN, ASSIGNOR TO CRYSTAL WASHING MACHINE COMPANY, OF DETROIT, MICHIGAN, A CORPORATION OF MICHIGAN.

WRINGER SUPPORT.

Application filed March 30, 1917. Serial No. 158,607.

To all whom it may concern:

Be it known that I, HERMAN A. SPERLICH, a citizen of the United States, and residing at Highland Park, in the county of Wayne and State of Michigan, have invented a new and Improved Wringer Support, of which the following is a specification.

The present invention relates to gearing for washing machines which comprise a tub and a wringer mounted on said tub to swing about a vertical axis, and it consists in means whereby a more rigid support is secured for the swinging wringer than heretofore. The invention further consists in the details of construction shown, described and claimed.

In the drawings, Fig. 1 is a side elevation of a preferred embodiment of the invention. Fig. 2 is a plan corresponding thereto. Fig. 3 is a fragmentary horizontal section showing the manner in which the wringer is mounted. Fig. 4 is a section on the line 4—4 of Fig. 3, the wringer being swung around 90°.

The tub frame Figs. 1, 2, 3, and 4 includes the front posts 1 and the rear posts 2 the upper ends of which are preferably joined by a single continuous angle bar 3 to which the upper edge of the tub (which comprises the central portion 4 and ends 5) is riveted. Suitable bars 6 and 7 connect the posts at one side and form a support for certain portions of the driving mechanism; and at the opposite side the posts may be connected by a bar (not shown). The posts 1 are also joined below the tub by an angle bar (not shown) and the posts 2 are similarly connected at the same level. Extending across between the last named bars is a wooden board 12 upon the front portion of which an electric motor 13 is secured in any desired way. It will be observed that the bottom of the tub is of semi-cylindrical form.

The washing cylinder revolves about a horizontal axis, and preferably includes the metal body portion 15 and ends 16, one of the latter having projecting therefrom a spindle 18 which is supported in a bracket 19 on the inner face of the tub. The other end of the cylinder is detachably connected to and driven by a driving shaft 22 that passes out through the end wall 5 of the tub.

Said shaft is driven by the motor through the medium of suitable shafting and reduc-

tion gearing enclosed within the casing elements 45—46—25—80 and controlled by the clutch lever 74. These features are described and claimed in my divisional applications, S. N. 233,731 and 233,733 filed March 21, 1918. The same gearing drives the inclined wringer driving shaft 92 (preferably rectangular in cross-section) that extends upwardly from the casing element 25—80 and is controlled for rotation in either direction by a reversing clutch lever 88.

The upper end of the shaft 92 has a bevel gear 93 mounted in a casing element 94 bolted to the upper rear corner portion of the frame and the bevel gear 93 meshes with a bevel gear 95 that is free to rotate about a pivot bolt 96, the upper end of which passes through a cap 98 for the casing element 94. The cap 98 rests at its lower face upon the upstanding arcuate flange 94' which is arranged concentrically with the pivot 96 and forms the side wall for the cavity which houses the bevel gear 95. Integral with the cap 98 is a combined shaft casing and wringer supporting arm 99, and depending from the latter is a brace arm 100 through which and the overhanging arm 101 on the element 94 the pivot bolt 96 passes. The gear 95 also preferably has teeth 102 of less pitch diameter than the teeth which engage the gear 93, and meshing with the latter is a bevel gear 103 rigid with the shaft 104 of one of the wringer rollers 105. The hub of the gear 103 fits in a bearing in the arm 99 and is slotted at 103' to receive a pin 103'' that passes through the shaft—this allows the shaft 104 to be easily assembled with reference to the gear. The other wringer roller is also positively driven through the medium of the spur gears 106 and 108. (Fig. 4.) It will thus be seen that the wringer frame 109 may be swung about the bolt 96 to allow its use in three positions ninety degrees apart in a manner well known in the art. A spring pressed dog 111 pivoted at 112 is arranged to be received in any of the notches 113 to hold the wringer frame in adjusted position. By this construction a stronger support for the wringer is secured than heretofore, since the pivot bolt 96 is supported both above and below the gear 95 and since the wringer supporting arm 99 is supported on the pivot bolt at two points a considerable distance

100

105

110

apart. The bearing of the cap 98 on the element 94 being removed considerably from the axis of the pivot also greatly relieves the latter.

- 5 Shaft casing sections 115 and 116 extend between and in sealing engagement with the casing 45—46 and the casing 25—80 and between and in sealing engagement with the latter and the casing element 94. Thus it
10 will be seen that the several casings may be substantially filled with thick lubricant.

An ordinary snap switch 120 may be mounted on the upper face of the arm 101 and the motor circuit wires (not shown)
15 may be led therefrom to the motor in any preferred way.

When the current is turned on the motor, the shaft 92 is rotated in either direction or is allowed to remain motionless, depending
20 on the position of the lever 88; thus the wringer rollers are driven in either direction at will or are permitted to remain idle.

The details of construction may be varied
25 within wide limits in some respects without departing from the spirit of the invention for example, the electric motor may be replaced by any other suitable motive power; I do not, therefore, wish to be limited except
30 as indicated by the subjoined claims.

I claim:—

1. In a device of the character described, a support, a casing element attached thereto, said casing element having an upwardly
35 opening cup shaped depression therein and also having an arm overhanging said depression, pivot forming means having a substantially vertical axis, said pivot forming means passing through the arm and through the central portion of the bottom wall of the depression, a bevel gear in said depression, said gear being rotatable about the axis of said pivot forming means, a second bevel gear meshing therewith, a sub-
40 stantially horizontal shaft for said second bevel gear, a casing for said shaft, said shaft casing including a cap for the cup shaped depression in the first mentioned casing element, said cap being rotatable, about the axis of said pivot forming means, and resting on the edge portion of said first mentioned casing element, said pivot forming means passing through the central portion of the cap, a frame supported by said shaft casing, and a pair of rollers therein driven in opposite directions by said shaft.
- 50

2. In a device of the character described, a support, a casing element attached thereto, said casing element having an upwardly
60 opening cup shaped depression therein and also having an arm overhanging said depression, pivot forming means having a substantially vertical axis, said pivot forming means passing through the arm and through the central portion of the bottom wall of

the depression, a bevel gear in said depression, said gear being rotatable about the axis of said pivot forming means, a second bevel gear meshing therewith, a substantially horizontal shaft for said second bevel gear, a casing for said shaft, said shaft casing including a cap for the cup shaped depression in the first mentioned casing element, said cap being rotatable about the axis of said pivot forming means and resting on the edge portion of said first mentioned casing element, said pivot forming means passing through the central portion of the cap, said shaft casing including an arm which extends below said first mentioned casing element and engages said pivot forming means at that point, a frame supported by said shaft casing and a pair of rollers therein driven in opposite directions by said shaft.

3. In a device of the character described, a bevel gear arranged to rotate about a vertical axis, pivot forming means for supporting said gear, a second bevel gear meshing with said first bevel gear, a substantially horizontal roller shaft, a second roller shaft substantially parallel to the first and rotatable therewith but oppositely thereto, a frame in which said roller shafts are mounted, said frame being rotatable about the axis of said pivot forming means, and means co-operating with said frame at a point above said first mentioned bevel gear for holding said frame in any one of a plurality of positions of adjustment.

4. In a device of the character described, a substantially horizontal roller shaft, a second substantially horizontal roller shaft rotatable with the first but oppositely thereto, a frame in which said roller shafts are mounted, a supporting element having an upwardly opening cup-shaped depression therein, said frame having a downwardly opening depression registering with the first named depression to form a gear chamber, the frame bearing on the upper face of the support around the depression therein, and being rotatable in respect thereto about a vertical axis, and a pair of bevel gears in the gear chamber for driving the first named roller shaft.

5. The combination of a vertical shaft and a bevel gear thereon, a frame having extensions above and below the gear in which the shaft is mounted, a horizontal shaft mounted in said frame and a bevel gear thereon meshing with the bevel gear on the vertical shaft, an inclined third shaft and a bevel gear thereon meshing with said bevel gear on the vertical shaft, a support for said third shaft having extensions above and below the gear on the vertical shaft and through which the vertical shaft extends and an arcuate supporting means in supporting relationship with said frame.

6. The combination of a vertical shaft and a bevel gear thereon, a frame having extensions above and below the gear in which the shaft is mounted, a horizontal 5 shaft mounted in said frame and a bevel gear thereon meshing with the bevel gear on the vertical shaft, an inclined third shaft and a bevel gear thereon meshing with said gear on the vertical shaft, and a support for 10 said third shaft having an extension between the supporting extensions on the frame and journaled on the vertical shaft, said frame and said support for the third shaft being provided with cup-shaped members 15 to enclose the gears.

7. In a wringer support, in combination, a supporting bracket, a wringer supporting bracket, swingingly carried by said first mentioned bracket, one of said brackets having 20 spaced arms and the other of said brackets having an arm lying between said spaced arms and pivotally connected thereto, a wringer supported by said wringer bracket having a roll shaft extending to said 25 wringer bracket, a driving shaft extending to said supporting bracket and disposed at

an angle to said roll shaft, power transmitting means between said driving shaft and said roll shaft, said brackets being provided with co-operating cavities for housing said power transmitting means. 30

8. In a wringer support, in combination, a bracket having spaced arms, a wringer supporting bracket having an arm lying between said spaced arms and pivotally connected thereto, a roll shaft extending into said wringer bracket, a driving element, power transmitting elements between said driving element and said roll shaft, said arms being provided with cooperating cavities forming a housing for said power transmitting elements, a spaced arm on said wringer bracket pivotally connected to said first mentioned bracket, a supporting extension on one of said arms providing a wall 45 for one of said cavities and being disposed in supporting relationship with another of said arms and means mounted on one of said brackets and cooperating with another for locking said brackets against relative 50 movement.

HERMAN A. SPERLICH.
